COMBINED BENCH SCALE AND
CONTROL CONSOLE

Darrell E. Smith, Bountiful, Utah, assignor to Hardy
Scales Company, Maywood, Calif., a corporation
of California

Continuation of design application Ser. No. 4,437,
Oct. 26, 1966. This application Sept. 13, 1967, Ser.
No. 8,611

Term of patent 14 years

(Cl. D52—10)

FIG. 2.

FIG. 3.

FIG. 1.

FIG. 1 is a perspective view of a combined bench scale and control console showing my new design;

FIG. 2 is a front elevational view thereof; and

FIG. 3 is an elevational view taken from one side thereof, the opposite side being a mirror image of the side shown.

This is a continuation of design application Serial No. D. 4,437, filed Oct. 26, 1966, now abandoned.

I claim:

The ornamental design for a combined bench scale and control console, substantially as shown and described.
